UNITED STATES PATENT OFFICE.

JENNINGS NELSON, OF CHICAGO, ILLINOIS.

SIGNAL SYSTEM.

Application filed July 10, 1925. Serial No. 42,631.

This invention relates to a signal system which may be used with particular advantage in the operation of an automobile. It is associated with the motor lubricating system, and includes in its assembly an indicator which may be located close to the operator.

A primary purpose of the present signal system is to convey a warning whenever there is a failure of oil pressure. For safe operation, a certain pressure should be maintained in the lubricating system of any motor. If the pressure, therefore, falls below a safety limit, or ceases altogether, the operator should be warned immediately so that the motor may be stopped to thereby avoid injury to its moving parts. The signal system of my invention is accordingly designed to afford an indication of any such changes in oil pressure conditions as call for an immediate shutting down of the power plant.

A preferred embodiment of my invention is shown in the accompanying drawing in the manner following:

25 Figure 1 is a central vertical section through the switch component;

Fig. 2 is a transverse section therethrough on line 2-2 of Fig. 1; and

30 Fig. 3 is a layout of the entire system including the electrical connections which extend between its component units.

The switch A shown in Fig. 1 includes a tubular housing wherein is a vertically disposed cylindrical chamber 4. An inlet 5 to the chamber is provided near the lower end thereof, as is also an outlet 6 at a point of somewhat higher elevation. In connection with the inlet is a pipe 7 to which oil is delivered from a pump B, a second pipe 8 extending from the outlet 6 to deliver oil to the various points desired. The pump is connected with a motor (not shown) so as to be driven thereby to furnish a circulation of oil to its several bearings, etc.

45 Slidably fitted within the chamber 4 is a plunger 9. Under conditions of little or no pressure, the plunger will drop so that its lower end is rested upon a cross bolt 10 which extends transversely through the housing. As shown best in Fig. 2, this bolt is insulated by means of a pair of bushings 11 wherein it is mounted. At one end of the bolt is a head 12, its other end being threaded to receive a nut 13 having means for connecting with an electrical conductor 14. The bolt assembly is such that the two bushings

are held snugly within their seats to make an oil-tight fit, when the nut is tightened upon the bolt. When the plunger is rested against the bolt, the circuit is, of course, completed to the ground.

The upper end of the housing which is open is threaded to receive a closure cap 15 which is fitted with the aid of a gasket 16 so as to render this connection oil-tight. Within the closure cap is a chamber 17 extending above the upper end of the housing so as to communicate with a by-pass 18 which extends vertically through the housing wall to connect with the outlet 6.

The conductor 14 leads to a signal device C which may conveniently be a lamp, buzzer, or the like. From this signal a connection 19 is carried to one pole of a motor ignition switch D. From its other pole a conductor 20 leads to a source of electrical energy E. The conductor 19 is also in connection with an ignition coil F. A wiring diagram in which the above described connections are contained is set forth in Fig. 3, and is suggested as one which is suitable for the purpose of this invention.

The operation of the present signal system is as follows: With closing of the ignition switch, a circuit is completed through the signal C and switch A to the ground whereby the signal is set in operation. As soon as the motor is running under its own power, however, the pump B sends oil under pressure through the pipe 7 to lift the plunger 9, thereby opening the switch. The plunger may rise in the housing to about the height indicated by dotted lines in Fig. 1, where a passage is cleared for the circulation of oil through to the outlet 6. The plunger will remain in this position indefinitely, that is, as long as the oil pump continues to function. While so elevated, the signal is inactive, thus indicating the proper functioning of the oil system.

If, for any reason, whether through failure of the pump, insufficient oil, or otherwise, the pressure should fall below the amount requisite for the continued suspension of the plunger, the circuit through the conductor 14 will be reestablished to operate the signal. The warning thus given is informative of a change in conditions which calls for immediate stopping of the motor, if damage is to be avoided.

At other times, moreover, with the oiling system in proper working order, the present

signal system will perform a useful service, as, for example, when the operator prepares to leave the car in the belief that the ignition switch is turned off when the engine is stopped. Should this not be the case, the signal will be operating, thus warning him that current is still passing through the ignition coil. Likewise should the operator stop his automobile, where there is considerable noise about him, his engine might stop without his being aware of that fact. With the present signal system, however, this could not happen, because the operator would be warned at once of the true conditions.

15 It will be noted that the present switch A comprises but one moving part, namely, the plunger 9. As the surfaces against which it moves are constantly flushed with oil, it requires no lubrication on its own account.

20 Should there be a slight leakage of oil, past the upper end of the plunger, this will be returned to the outlet 6 through the by-pass 18. I prefer that the movement of the plunger should be in a vertical direction so as to utilize the force of gravity rather than a spring to oppose the oil pressure which is exerted upon the under side of the plunger. This makes for simplicity and economy and also for greater durability in the structure.

25 30 The cross bolt 12 with which the plunger makes electrical contact serves also as a stop which limits downward movement of the plunger to a point where oil is always permitted to enter the chamber 4 through the inlet 5 to exert an upward pressure on the plunger. By combining and arranging the parts in the manner described, I reduce to a minimum the number of elements which are necessary in the operation of the present device. It may, of course, be variously modi-

fied, but in so far as such changes respond to the terms of the appended claims, I would include them all within the scope of this patent.

I claim:

1. In an oil line, an interposed housing having a cylindrical chamber open at one end, there being inlet and outlet openings communicating with the chamber, and a by-pass between the outlet and the open housing end, a closure removably fitted to the open housing end in a manner to preserve communication between the by-pass and chamber therewithin, a plunger movable within the chamber to open or close the outlet in response to variations in pressure of oil entering through the inlet, and means engaged by the plunger when closing the outlet to establish an electrical circuit, substantially as described.

2. In a pipe line, an interposed housing having a chamber through which fluid is circulated, there being inlet and outlet connections to the housing chamber, a bolt extending through the housing with its opposite ends disposed exteriorly thereof, a pair of bushings forming mountings for the bolt and each seated within an opening in the housing walls, a head on one end of the bolt, a nut screw threaded on the other bolt end and adapted, when tightened to hold the two bushings closely within their seats in a manner whereby leakage of oil is prevented, and means movable within the housing chamber in response to variations in fluid pressure adapted with failure in such pressure to contact with the bolt whereby an electrical circuit is completed, substantially as described.

JENNINGS NELSON.
